(57) **CLAIM**

The ornamental design for a stand mixer, as shown and described.

DESCRIPTION

FIG. 1 is a top-front perspective view of a stand mixer showing our new design according to a first embodiment; FIG. 2 is another top-front perspective view thereof; FIG. 3 is a front elevation view thereof; FIG. 4 is a rear elevation view thereof; FIG. 5 is a right side elevation view thereof; FIG. 6 is a left side elevation thereof; FIG. 7 is a top plan view thereof; FIG. 8 is a bottom plan view thereof; FIG. 9 is a bottom-rear perspective view thereof; FIG. 10 is a bottom-front perspective view thereof; FIG. 11 is a front perspective view of a stand mixer showing our new design, shown without the container for clarity and completeness of disclosure; FIG. 12 is another top-front perspective view thereof; FIG. 13 is a front elevation view thereof; FIG. 14 is a rear elevation view thereof; FIG. 15 is a right side elevation view thereof; FIG. 16 is a left side elevation thereof; FIG. 17 is a top plan view thereof; FIG. 18 is a bottom plan view thereof; FIG. 19 is a bottom-rear perspective view thereof; and, FIG. 20 is a bottom-front perspective view thereof. The dashed broken lines in the figures illustrate portions of the stand mixer that form no part of the claimed design.
